UNITED STATES PATENT OFFICE.

EDWARD E. HINRICHSEN, OF NEW YORK, N. Y., ASSIGNOR TO WESTERN ELECTRIC COMPANY, OF NEW YORK, N. Y., A CORPORATION OF ILLINOIS.

TELEPHONE-EXCHANGE SYSTEM.

1,161,214.

Specification of Letters Patent. Patented Nov. 23, 1915.

Application filed June 12, 1915. Serial No. 33,725.

To all whom it may concern:

Be it known that I, EDWARD E. HINRICHSEN, a citizen of the United States, residing at New York, in the county of New York 5 and State of New York, have invented certain new and useful Improvements in Telephone-Exchange Systems, of which the following is a full, clear, concise, and exact description.

10 This invention relates to telephone exchange systems, and more particularly to such systems in which common battery and magneto telephone lines terminate at the same position of a switchboard at a central office, such lines being adapted to be connected with lines terminating at another position 15 of the same or different switchboard.

It is an object of this invention to provide an improved trunk circuit by means of 20 which connection may be made between a link connecting circuit on the one end and either a common battery or magneto telephone line on the other end, and over which supervision may be had from either 25 character of local telephone line to the link connecting circuit.

In telephone exchange systems heretofore used, where common battery and magneto lines terminate on the same switchboard, several methods have been in use for furnishing 30 service between these lines and toll lines. Where the toll board is a part of the local switchboard, one method which has been in use is to multiple all of the local lines—both 35 common battery and magneto—through the various toll positions, and to use toll cords one end of which would distinguish between the common battery and magneto lines.

Where the toll board is separate and distinct 40 from the local board, one method in use is to use trunks terminating in jacks at both boards, to use at the toll board cords which distinguish between toll and trunk lines, and to use at the local boards cords 45 which distinguish between common battery and magneto lines. This method has its disadvantages in that there is no direct supervision from the toll cord, the local operator supervising all connections. On toll connections it is important that all supervision 50

should be by the toll operator. Another method has been to multiple all local lines through the various positions of the toll board. Still another method has been to use separate trunks for handling calls to and from magneto and common battery lines, the trunks being plug-ended at the local board and adapted for connection directly with the local lines. Such a method is open to the objection that the trunks cannot be 60 multiplied through the toll board, for all supervisory signals are associated directly with the trunks.

While the scheme of multiplying all local lines through the various positions of the toll 65 board is an excellent one, still it means a high first cost for equipment.

In accordance with this invention, the common battery and magneto telephone lines terminate at regular subscribers' positions of 70 a switchboard, while the toll lines terminate at a toll position of the same board or at a different switchboard located in either the same or a different central office. Extending between the local and the toll position is a 75 trunk circuit, plug-ended at the local board for connection to either a common battery or a magneto telephone line. At the toll position is a toll link connecting circuit for connecting a toll line with a trunk circuit. 80 Supervisory signals associated with the toll link circuit are controlled from the common battery and magneto telephone lines through the agency of apparatus located in the trunk and toll link circuits.

This invention will be more fully understood by reference to the accompanying drawing illustrating one embodiment of the invention and wherein all apparatus is shown in its normal and unactuated condition.

In the drawing there is shown a common battery substation A and a magneto substation B, both terminating in a local position C of the switchboard. A trunk circuit D extends from the local position C to a toll position E. At the toll position is located a toll cord circuit F. For the purpose of the present invention, only one end of the cord circuit is shown, the other end of the cord 100

circuit and the toll lines, to which it is adapted to be connected forming no part of this invention. The trunk circuit D and the cord circuit F are adapted to complete the connections originating at either the local or toll position.

Assuming that a call has been received at position E for connection with substation A, the operator at position E inserts the plug of the cord circuit F into the jack of the trunk circuit D, whereupon relay 5 operates, lighting both supervisory signals 6 and 7 the former located at the toll position E and the latter at the local position C. The operation of relay 5 by the opening of contact 31 disconnects relay 15 from the ring side of the trunk circuit D. The energizing circuit of relay 5 includes the winding of relay 8 and supervisory lamp 9 in parallel. The resistance of the two windings of relay 5 is such that relay 8 is not actuated and supervisory lamp 9 is not lighted. Insertion of the plug into the jack opens contact 30, whereby the ground connection is removed from the tip side of the trunk circuit D. The operator at position C, observing the signal 7, actuates listening key 10, bridging the operator's telephone set across the talking strands of the trunk circuit, and operating relay 15 over a circuit from battery 16 through the winding of relay 15, contact 17 of relay 5, contact 18 of listening key 10 to ground. Relay 15 in operating, completes a locking circuit for itself which may be traced from battery 16, winding of relay 15, contact 17 of relay 5 and contact 19 of relay 15 to ground. The operator at position E having thrown listening key 11 thereat the operator at position C may receive instructions from the operator at position E as to the number of the wanted line. The operator at position C, having been advised that the trunk is to be connected to subscriber A's line, releases listening key 10 and inserts the plug of the trunk C into the jack of A's line whereupon relay 20 operates. Relay 20 in operating, short-circuits the right-hand winding of relay 5, thereupon lowering the resistance of the operating strand of the toll 50 end of the trunk circuit D to such an extent that relay 8 operates to connect a battery to the talking strands of the cord circuit F through the windings of relay 25, and supervisory lamp 9 lights to furnish a ringing signal to the toll operator. The called subscriber may now be signaled by the toll operator in the usual manner. When responding, the called subscriber, in removing the receiver from the switch-hook, causes the operation of relay 25 which effaces supervisory signal 9. When the conversation is completed, subscriber A restores the receiver to the switchhook, whereupon supervisory signal 9 lights to furnish a disconnect signal 65 to the toll operator. The operator at posi-

tion E, in removing the plug of the cord from the jack of the trunk circuit, deenergizes relay 5, whereupon signals 6 and 7 are actuated, signal 7 furnishing a disconnect signal to the local operator. The circuit 70 through the signals 6 and 7 includes contact 26 of relay 5 and contact 27 of relay 20. The operator at position C may now remove the plug from the jack of A's line, whereupon all apparatus returns to its normal 75 condition.

If it had been desired to complete the connection to subscriber B instead of to subscriber A, the operations would have been the same up to the point where the operator 80 at position C inserts the plug of trunk circuit D into the jack of the called line. The insertion of the plug into the jack of B's line does not operate relay 20 for the sleeve circuit of B's line is open. Subscriber B 85 may be signaled in the usual manner. When the conversation is completed, subscriber B gives a disconnect signal to the operator at position F by operating the generator 28 which causes the operation of disconnect 90 signal 29. The operator at position F removes the plug from the jack, whereupon relay 5 is deenergized as before explained. The removal of the plug from the jack also closes contact 30, whereupon relay 15 is actuated over a circuit which may be traced from battery 16, through the winding of relay 15, contact 31 of relay 5, out over one side of the line through the call bell 32 at station 95 B, and back over the other side of the line to ground through contact 30. The operation of relay 15 causes the operation of signals 6 and 7, the circuit for these being closed at contact 26 of relay 5 and contact 19 of relay 15. The operator at position C observing 100 disconnect signal 7, may now remove the plug in the usual manner, whereupon all apparatus is returned to normal condition.

Should subscriber A initiate a call, the operator at position C is signaled in the usual 110 manner, whereupon the call is answered in the usual manner by inserting the answering plug of a cord circuit (not shown). The operator ascertaining that a toll connection is desired, withdraws the answering plug of the cord and inserts the plug of the trunk circuit D into the jack of the line, causing the operation of relay 20 which short circuits the right hand winding of relay 5 and causes the operation of signals 6 115 and 7. Relay 15 also operates but performs no function where subscriber A initiates a call. The toll operator at position E observing signal 6, inserts the plug of cord circuit F into the jack of the trunk circuit 120 D, whereupon relay 5 is energized to efface the signals 6 and 7. When the plug of the cord circuit is inserted in the jack of the trunk circuit, relay 8 is energized, whereupon relay 25 is actuated to prevent the op- 125 130

eration of supervisory lamp 9. The operator at position E, after receiving the proper instructions completes the connection in the usual manner. When the conversation is completed subscriber A restores the receiver to the switchhook whereupon supervisory signal 9 at position E operates to furnish a disconnect signal. The connections may be taken down in the manner hereinbefore explained.

Should subscriber B initiate the call, the central office is signaled in the usual manner, whereupon the operator answers by inserting the plug into the jack of B's line. Relay 15 is thereupon energized over a circuit including the line wires and contact 30 of the jack of the trunk D. The operation of relay 15 causes the operation of the signals 6 and 7. The operator at position E, observing signal 6, inserts the plug of cord circuit F into the jack of trunk circuit D, thereby operating relay 5 which effaces signals 6 and 7. The connections then may be completed by the operator at position E in the usual manner. When the conversation is completed, subscriber B operates the generator 28 which actuates the disconnect signal 29. The operators at positions E and C then take down the connections in the manner hereinbefore explained.

It will be seen that by using a system embodying the present invention a single trunk circuit may be used for completing the connections from both common battery and magneto lines to a toll position and from a toll position to both common battery and magneto lines. Also that the operator at the toll position has entire supervision over the connection established from a toll line to either a common battery or magneto line.

What is claimed is:

1. In a telephone exchange system, different types of telephone lines terminating at a local position of a switch-board, a trunk circuit extending from the local position to a second position, a link circuit adapted at said second position for connection with said trunk circuit, a supervisory signal associated with said link circuit, and switching means associated with said trunk circuit operating upon connection of said trunk circuit with a predetermined type of line for placing said supervisory signal under control of the connected line when said link and trunk circuits are connected.

2. In a telephone exchange system, different types of telephone lines terminating at a local position of a switchboard, a trunk circuit extending from the local position to a toll position, a toll link circuit adapted for connection with said trunk circuit, supervisory signals of different character associated with said toll link circuit, and switching means associated with said trunk circuit operating upon connection of said trunk circuit

circuit with a predetermined type of line for placing one of said supervisory signals of the connected link circuit under control of the connected line.

3. In a telephone exchange system, common battery and magneto telephone lines terminating at a local position of a switchboard, a trunk circuit extending from the local position to a toll position, a toll link circuit adapted for connection with said trunk circuit, two supervisory signals of different character associated with said link circuit, and switching means associated with said trunk circuit and operating upon connection of said trunk circuit with a common battery line for placing one of said supervisory signals of the connected link circuit under control of the common battery line and operating upon connection of said trunk circuit with a magneto line for placing the other of said supervisory signals under control of the magneto lines.

4. In a telephone exchange system, different types of telephone lines terminating at a local position of a switchboard, a trunk circuit extending from the local position to a toll position, a toll link circuit adapted for connection with said trunk circuit, two supervisory signals associated with said toll link circuit, an operating strand for the toll end of said trunk circuit, a relay associated with said trunk circuit operating upon connection of said trunk circuit with a predetermined type of line to alter the resistance of said operating strand, and a relay associated with said link circuit responsive to the altered condition of said operating strand when said link circuit is connected with said trunk circuit, the actuation of said link circuit relay placing one of said supervisory signals under control of the connected telephone line.

5. In a telephone exchange system, different types of telephone lines terminating at a local position of a switchboard, a trunk circuit extending from the local position to a toll position, an operating strand for the toll end of said trunk circuit, and switching means associated with the local position end of said trunk and operating when said trunk is connected to a predetermined type of line to reduce the resistance of said operating strand, a toll link circuit adapted for connection with said trunk circuit, a supervisory signal and a relay associated with said link circuit, and a circuit for said relay including said operating strand, the reduced resistance of said operating strand permitting the operation of said relay whereby when said link circuit is connected with said trunk circuit said relay operates to place said supervisory signal under control of the connected line.

6. In a telephone exchange system, different types of telephone lines terminating

at a local position of a switchboard, a trunk circuit extending from the local position to a second position, a link circuit at said second position adapted for connection with said trunk circuit, and switching means associated with said trunk circuit operating upon connection of said trunk circuit with a

predetermined type of line for rendering said connected link circuit operable with the predetermined type of telephone line. 10

In witness whereof I hereunto subscribe my name this 11th day of June, A. D. 1915.

EDWARD E. HINRICHSEN.
